UNITED STATES PATENT OFFICE.

CHARLES ESPLIN, OF MINNEAPOLIS, MINNESOTA.

SHAFT-HANGER.

SPECIFICATION forming part of Letters Patent No. 366,656, dated July 19, 1887.

Application filed November 1, 1886. Serial No. 217,686. (No model.)

To all whom it may concern:

Be it known that I, CHARLES ESPLIN, of Minneapolis, in the county of Hennepin and State of Minnesota, have invented certain Improvements in Shaft-Hangers, of which the following is a specification.

My invention relates to certain improvements in adjustable shaft-hangers; and it consists, generally, in constructing a hanger of this description which shall have a ready and positive means of adjustment in all directions, and avoiding the possibility of clamping the journal or bringing unnecessary strain upon any part of the journal or hanger.

My invention further consists in the combination and arrangement hereinafter described, and particularly pointed out in the claims.

As adjustable hangers have heretofore been constructed the journal-bearing is supported in a swiveling yoke by means of set screws through the two arms of the said yoke, which bear at their points against the journal-box in the plane of the center of the axle, and the lateral adjustment is attained by loosening one set-screw and tightening the other. In this operation there is a liability of springing or compressing the journal-box and causing the journal to heat and to exert an undue strain upon the yoke by the tendency to spread the two arms apart. To overcome this, it is necessary to make the hanger heavier than would be the case if the strain were more equally distributed. The vertical adjustment in these hangers is made by a similar set-screw bearing upon the under side of the yoke, by which the said yoke and journal-box are raised to the proper height, thus causing the entire weight of the shaft and journal-bearing to rest upon the end of this set-screw. In some styles of hangers it is inconvenient or impossible to make this arrangement. In my improvement I have overcome all these objections and provide a hanger which can be used and adjusted equally well either for a floor, bracket, or overhead hanger.

In the drawings which form a part of this specification, Figure 1 is an end elevation of my improved hanger. Fig. 2 is a side elevation, and Fig. 3 is a cross-section taken on line xx of Fig. 2. Fig. 4 is a detail showing a modified construction.

I have shown only so much of the hanger as embodies my improvement. The base or socket can be adapted to any of the different styles in common use.

In the drawings, A represents the shaft, and B the journal bearing or box having a cap, B', in the usual manner.

C is a yoke which embraces the journal-box, and is provided with ears or lugs C' C''.

D is a bearing pin or bolt constructed to receive a wrench at one end and provided with the shoulder D', and screw-threaded at the other end. This bolt passes through the lugs on the yoke C. The lug C' is bored to fit the larger portion of the said bolt, and the lug C'' has a screw-threaded opening which receives the threaded end of the bolt. The bolt is prevented from turning by the set screw C''. The bolt D also passes through the journal-bearing B centrally and at right angles with the shaft A, and is secured to the said journal-bearing by the shoulder D' and nuts or collars D'' D''''. By means of these double nuts the journal-bearing may be held rigidly in its position against the shoulder D', but may be free to oscillate upon the bearing-bolt.

E is a spindle, made, preferably, in one piece with the yoke C and screw-threaded at its lower end to receive the nut E', which may be further secured by the pin E''.

F is a sleeve which fits upon the spindle E between the under side of the yoke and the nut E', and in which the said spindle is allowed to swivel. The upper end of this sleeve is preferably provided with a collar, F', and from the collar to its lower end the external surface is screw-threaded.

F'' is a set-screw through the collar F', which bears upon the spindle, which may be used to hold the yoke in place after it has been adjusted.

G is a socket or base of the hanger, having an internal screw-thread, into which the sleeve F fits.

The operation is as follows: After the hanger is placed in position the fine adjustment necessary to bring it to perfect line may be attained for the perpendicular variation by turning the sleeve F to the right or left, as the case may be. The exterior of this sleeve being screw-threaded, this operation causes it to raise

or lower in the socket G and to carry with it the spindle E and the yoke and journal-bearing attached thereto until the proper height is reached. The spindle E is free to swivel in the sleeve, and will thus adjust itself to any horizontal angle required. The lateral adjustment is made by turning the bearing-bolt D. This bolt, which is held in the journal-bearing by means of the shoulder D' and set-nuts D'' D''', is free to revolve in said journal-bearing; but any end motion of the bolt causes a corresponding movement of the journal-bearing, and, as one end of the said bolt is screw-threaded in the lug C'' of the supporting-yoke C, turning the bolt to the right or left causes it to advance or recede in the said lug and carry with it the journal-box. This operation is continued until the journal-bearing is brought to the exact line.

20 The journal-bearing oscillates upon the bolt D and accommodates itself to any vertical angle with the shaft. After the adjustment has been completed, the set-screws C''' and F'' may be driven to clamp the bearing-bolt and 25 spindle and prevent the adjustment from being changed.

It will be seen that in my journal-bearing the strains are all carried in the direction of the weight and no undue stress is exerted upon 30 one portion to support another, and by screw-threading the sleeve F and operating it from the top I am enabled to adapt my hanger to places where it would be impossible to get the ordinary form of vertical adjustment.

35 By securing the yoke to the socket or base of the hanger in the manner described, the nut E' bears upon the under side of the spindle E,

and is thus held in position against any upward pull upon the journal-bearing, as the yoke cannot be forced from the socket without first 40 stripping the thread upon the sleeve. This enables me to use my hanger with an up belt without a covering-bolt.

Where there is no liability to an upward strain or lift upon the shaft, I may use the 45 form of attaching the journal-bearing to the bolt D which is shown in Fig. 4, in which case the journal-bearing is provided with two lugs, and the bearing-bolt has a recess turned in its surface to receive the said lugs. This 50 does away with the use of the nuts or collars D'' D''', and may in some instances be preferable.

What I claim as my invention is—

1. The combination, in a shaft-hanger, of the vertically-pivoted yoke C, provided with the arms C' C'', the bolt D, extending through said arms and longitudinally adjustable therein, and the journal-box secured to the said bolt and moving therewith, but capable of oscillating freely thereon, substantially as described.

2. In a shaft-hanger, the combination of the journal-box B, the pivoted yoke C, the bearing-bolt D, attached to said journal-box and 65 adjustable in said yoke, the screw-threaded sleeve F, adjustable in the base G, and the nut E', attached to the spindle E of said yoke and bearing upon the sleeve F, substantially as described.

CHARLES ESPLIN.
